UNITED STATES PATENT OFFICE.

EDGAR P. BINFORD, OF CHICAGO, ILLINOIS.

CENTRIFUGAL CASTING APPARATUS.

986,130.

Specification of Letters Patent. Patented Mar. 7, 1911.

Application filed March 23, 1908. Serial No. 422,772.

To all whom it may concern:

Be it known that I, EDGAR P. BINFORD, a citizen of the United States, residing at Chicago, in the county of Cook and State 5 of Illinois, have invented new and useful Improvements in Centrifugal Casting Apparatus, of which the following is a full, clear, concise, and exact description, reference being had to the accompanying drawing, forming a part of this specification.

This invention relates to improvements in centrifugal casting apparatus.

For filling cavities, and especially large cavities, an improved process, known as the 15 "inlay" process, has recently come into use in dental work, which process comprises the taking of an impression of the cavity in wax or similar moldable material fusing at a low temperature, employing the wax 20 impression thus made as a pattern for casting a filling in gold or similar metal, and inserting this filling into the cavity in the tooth, the filling being then secured in place by some suitable method, as by the use of 25 cement. The best method thus far devised for casting the inlay is to place the wax impression in a flask and fill the flask around the impression or pattern with investment material—this material being preferably a 30 composition of plaster-of-Paris with other materials. The wax pattern is then removed by the application of heat, the wax being boiled or burned out through a suitable sprue-hole. The cavity formerly occupied 35 by the wax pattern is then used as a casting-mold, the cavity being filled with melted gold or other metal through the sprue-hole. Difficulty has heretofore been experienced in causing the melted metal to flow down 40 through the sprue-hole to the mold. The principal object of the present invention is to provide an improved process for casting inlay fillings in which this difficulty is overcome.

Another object is to provide suitable apparatus for carrying out my improved process, this apparatus being of simple construction, efficient in action and reliable in its 45 operation.

To these ends I provide a crucible, for the melting of the metal, in the flask itself, instead of melting the metal outside the flask and afterward introducing the same 50 into the flask in its molten state—as has in some instances been done. After the metal 55 has been melted in the crucible in the flask it

is then injected through the sprue-hole into the mold by the application of centrifugal force.

In the accompanying drawings, Figure 1 60 illustrates an approved form of the apparatus which I employ in carrying out the process of casting inlay fillings according to my invention, and shows one of the steps of said process; Fig. 2 is a sectional view of 65 the flask containing investment material and the wax pattern embedded therein, ready for burning or boiling out; Fig. 3 shows a modification of the device in which a flexible connection, consisting of a chain, 70 is employed in place of the stiff rod of the form shown in Fig. 1. In this figure the flask containing the mold and crucible is shown in section, the wax pattern having been removed; and Fig. 4 shows a further 75 modified form of the apparatus.

In the several figures of the drawings, in which like reference numerals indicate the same parts throughout, 5 is the flask, consisting of a metallic, comparatively thin ring 80 or tube, having its lower end flanged inwardly at 6 for a purpose hereinafter explained. The impression 7, forming the pattern, is surrounded by investment material 7^a. The upper portion of the mass of 85 investment material 7^a is hollowed downwardly to form a crucible 8, in which is to be melted the gold or other metal of which the inlay filling is to be composed. A sprue-hole leads downward from the crucible 8 90 to the space occupied by the pattern 7.

Adapted to be attached to the flask 5 is a removable bail 10, to which is secured one end of a bar, chain or the like 11, the other end of this member being swivelingly secured to the end 12 of a rod 13 having its opposite end provided with a handle 14 which may be grasped by the hand of the operator. The end of the rod 13 is preferably headed, as shown in Fig. 1, and is 100 grooved at 15 to prevent the member 11 moving along the rod toward the hand of the operator.

In the use of this apparatus, and the employment of my improved method of casting, the flask 5, with the bail 10 and handle attached thereto, and containing the wax impression 7 embedded in the investment material 7^a, is placed upon a heating device, such as a Bunsen burner 16, and the wax 105 impression is burned out, a blow-pipe flame being used, if necessary, to hasten the burn-

ing of the wax. When the wax of the pattern 7 has wholly disappeared, the space formerly occupied thereby forms the mold 17 (see Fig. 3) in which the filling is to be cast. A suitable quantity of gold 18 is placed in the crucible 8 and is there subjected to heat from the Bunsen burner and also, if desired, to the heat from the blow-pipe 19, until the gold melts. When the gold has been reduced to a molten condition the flask is removed from the burner by means of the rod 13, and a quick upward movement is given thereto, this sudden upward movement causing the molten metal to flow, by reason of its inertia and consequent reaction, down the sprue-hole into the mold. The flask is now whirled preferably in a vertical plane, around the rod 13 by a suitable rotary movement imparted to the handle by the hand of the operator, the rod 11 turning freely, by reason of its swiveling connection, on the rod 13. The centrifugal force resulting from the circular movement of the flask about the rod 13 forces the molten metal into the mold and holds it there until chilled and hardened.

The part which connects the end of the rod 12 with the bail 10 of the flask may consist either of a stiff rod, as shown in Fig. 1, or of a chain or similar flexible member, as shown in Fig. 3. When the rod is employed it is preferably made detachable from the bail 10, a convenient form of separable connection between these parts being afforded by forming the end of the rod into a normally closed loop or ring, and bending the part 21 away from the body of the rod. A similar form may be given the other end 22 of the rod 10, whereby the rod may be readily attached to or detached from the rod 13.

The inturned flange 6 around the lower edge of the flask prevents the mass of investment material from passing out of the flask under the influence of centrifugal force when the flask is whirled. A flask with a closed bottom would be undesirable as the bottom would interfere with the operation

of forming the mold of investment material around the pattern.

The bail 10 is made detachable to facilitate the operation of forming the mold. By moving the hooked ends 23 of the bail away from each other they may be readily unhooked from the openings in the edge of the flask in which they are secured.

In the form of apparatus shown in Fig. 4, the flask 5 is not provided with a bail, but is inserted into a receptacle 24 having an open bottom and provided with an inturned flange 24^a to prevent the flask passing therethrough. The receptacle 24 is provided with a bail 25, which may be detachable if desired and is attached to ears 26 extending from the sides of the receptacle. In the use of this form of device the pattern may be removed as hereinbefore described, and, while still hot, the flask may be inserted into the receptacle 24. The gold or other metal will now be placed in the crucible 8, and the blow-pipe flame directed upon the same until it melts. The receptacle 24, with the flask therein, will now be whirled around the handle until the metal cools, after which the flask will be removed and the casting taken therefrom by dissolving out the investment material.

Having thus described my invention, what I claim as new and desire to secure by Letters Patent is:

An apparatus for casting inlay fillings, comprising, in combination, a flask consisting of a ring provided with an inwardly flanged lower edge, and having a removable bail, a rod having a handle upon one of its ends for grasping the same, and connection between the opposite end of said rod and said bail.

In witness whereof, I have hereunto subscribed my name in the presence of two witnesses.

EDGAR P. BINFORD.
